UNITED STATES PATENT OFFICE.

EDWARD E. PALMER, OF WOOSTER, OHIO.

SHADE AND CURTAIN FIXTURE.

No. 918,692.

Specification of Letters Patent. Patented April 20, 1909.

Application filed May 14, 1908. Serial No. 432,772.

To all whom it may concern:

Be it known that I, EDWARD E. PALMER, a citizen of the United States, residing at Wooster, in the county of Wayne and State 5 of Ohio, have invented certain new and useful Improvements in Shade and Curtain Fixtures, of which the following is a specification.

My invention relates to improvements in 10 shade and curtain fixtures designed for use in connection with windows and similar places where it is desired to attach and suspend window-shades and curtains or draperies.

15 My invention relates more particularly to that class of shade and curtain fixtures in which the curtain-pole bracket is secured to the shade-roll bracket; and in my invention a shade-roll bracket is provided with a supporting-plate adjustably-secured and mounted 20 in front of the face of the window-frame by means of a second or main attaching and supporting-plate removably-secured beneath the lower edge of the upper cross-member of 25 the window-frame by means of a single screw, thus avoiding defacement of the window frame incident to attaching the ordinary fixture directly to the face of the window-frame.

30 The primary object of the invention is to produce a generally improved device of this class of simple construction adapted to support the shade-roll in either one of the two well known conventional styles of mounting; 35 and a further object of the invention is to provide a generally-improved attaching-device adjustably-supporting both the shade-roll and curtain-pole bracket, and which may be easily attached to or removed from any 40 ordinary window-frame. A single screw is required for each attaching device and this screw also performs the additional function of clamping shade-roll bracket in any position to which it may be moved horizontally 45 to conform to shade-rolls and curtain-poles of varying lengths.

With these and other ends in view, the invention consists in the novel construction, arrangement and combination of parts, hereinafter described, illustrated in the accompanying drawings, and particularly pointed out in the appended claims.

50 Referring to the drawings, forming a part of this specification, Figure 1, is a perspective 55 view of the improved fixture, embodying my

invention, as it appears attached to the upper left hand corner of a window frame. Fig. 2, a perspective view of the left hand main attaching and supporting-plate of the improved fixture. Fig. 3, a perspective 60 view of the right hand main attaching and supporting-plate. Fig. 4, a perspective view of the left hand slidably and adjustably-mounted shade-roll supporting bracket. Fig. 5, a perspective view of the right hand 65 slidably and adjustably-mounted shade-roll supporting-bracket. Figs. 6 and 8, are side views of the improved detachable curtain-pole brackets. Fig. 7, a rear end view of the same. 70

Similar numerals of reference designate like parts throughout all the figures of the drawings.

The improved fixture comprises a main attaching and supporting-plate removably-secured beneath the lower edge of the upper cross-member of the window-frame, a shade-roll supporting-bracket provided with a supporting-plate adjustably-secured to said main attaching and supporting-plate and carried in front of the face of the window frame, and a curtain-pole bracket detachably-mounted upon the bracket-head of said shade-roll supporting-plate. 75

The main attaching and supporting-plate 80 1, is provided at one side with an extension 2, preferably, bent at right angles to the main body portion and terminating in a downwardly-extending hooked flange 3. One end 85 of the main body portion is provided with an auxiliary bracket-head 4, preferably, extending at right angles thereto and depending therefrom as shown most clearly in Fig. 1, 90 of the drawings. The main body portion of plate 1, is adapted to be removably-mounted 95 beneath and attached to the lower edge of the upper cross-member of the window-frame by means of a screw 5, the shank of which passes through a recess-slot or guide-way 6, extending from the rear edge of the 100 plate 1.

The supporting-plate 7, of the shade-roll bracket is slidably and detachably-connected to the main attaching and supporting-plate and adjustably-secured and mounted in 105 front of the face of the window-frame by means of a horizontally-extending hooked-flange 8, taking into and slidably-engaging with the hooked-flange 3, the bent over edge 8^a, of said flange impinging against the at- 110

taching and supporting-plate 1. It will be observed that the hooked-flanges 3 and 8, provide recesses forming guide-ways 3^a and 8^b, respectively, for the reception of the edge 5 of the opposite engaging hooked-flange. It will be observed that the supporting-plate 7, rests against the face of a window-frame and, when it is desired to shift or adjust the supporting-plate, the screw 5, may be loosened and the plate 1, may be shifted horizontally to the position desired, after which it may be securely held in position by moving the same firmly into frictional engagement with the face of the window-frame by pressing 10 against the face-extension 2, and then securing the parts in their adjusted position by tightening the screw 5. One end of the supporting-plate 7, terminates in a bracket-head 9, preferably, projecting at right angles 15 thereto and provided with the usual opening or recess 10, for the reception of the ends of the shade-rolls.

The curtain-pole bracket comprises an upwardly-extending shank portion 11, and 25 an outwardly-extending hook or bracket portion 12, having a recess 13, for the reception of an ordinary wooden curtain-pole. The upper end of the hook portion 12, terminates in an upwardly-extending shank-portion 14, for taking through transverse openings of an ordinary brass tubular telescoping curtain-rod or pole, when it is 30 desired to use a curtain-pole of this style. The base of the curtain-pole bracket terminates, in the present instance, in a pair of rearwardly-extending guide-shanks 15, having their upper and lower edges bent over forming hooked guide-flanges 16, providing 35 guideways 16^a, for the reception of and slidably-mounted on the upper and lower edges of the bracket head 9. The intermediate recess-opening 17, is adapted to receive and take over the adjacent pins of the ends of the shade-roll mounted in the openings or recesses 10, when the curtain-pole bracket is 40 mounted on the bracket head 9, as indicated in Fig. 1, of the drawings. It will also be observed that when the curtain-pole bracket is mounted upon the bracket head 9, provided 45 with the usual recess-opening the upper guide-shank 15, will prevent the elevation or accidental removal of the pin of the shade-roll from the recess-opening, as clearly appears in Fig. 1, of the drawings.

55 From the foregoing description, taken in connection with the accompanying drawings, the operation and advantages of my invention will be readily understood.

I have entered into a somewhat detailed 60 description of the present and preferred embodiment of my invention in order to impart a definite understanding of the same. I do not desire, however, to be understood as restricting myself to the exact construction

shown and described, as various changes and 65 modifications may be made in the form, size, and minor details of construction without departing from the principles or sacrificing any of the advantages of this invention.

What I claim and desire to secure by Let- 70 ters Patent is,—

1. In a shade and curtain fixture, the combination with the upper cross-member of a window frame, and a main attaching and supporting-plate removably and adjustably-se- 75 cured beneath the lower edge of said cross-member and provided with a face extension terminating in a downwardly-extending hooked-flange in front of the face of said cross-member; of a supporting-plate carrying 80 a bracket head at one end and resting against the face of said cross-member and terminating at its lower edge in a hooked-flange slidably-engaging said first named hooked-flange and having its bent over edge impinging against 85 said attaching and supporting-plate.

2. In a shade and curtain fixture, a main attaching and supporting-plate comprising a horizontally-extending main plate carrying at its front edge an upwardly-projecting 90 face-extension terminating in a downwardly-extending hooked flange.

3. In a shade and curtain fixture, an at- 95 taching and supporting-plate provided with a downwardly-extending hooked-flange, and a supporting-plate carrying at one end a bracket head and provided at its lower edge with a hooked-flange taking into and engag- 100 ing with said hooked-flange and having the lower or bent over portion of said hooked-flange abutting against said attaching and supporting-plate.

4. In a shade and curtain fixture, a main attaching and supporting-plate comprising a main plate or body portion provided with a 105 recess or guide-slot extending from its rear edge, and carrying at its front edge an up- 110 wardly-projecting face-extension terminat- ing in a downwardly-extending hooked-flange and provided at one end with a de- pending bracket-head.

5. A shade and curtain fixture, comprising 115 an attaching and supporting-plate having one edge bent into a hooked-flange and one end bent into a bracket-head, a supporting-plate provided with a hooked-flange taking into and slidably-mounted in said first named hooked-flange and provided at one end with a bracket-head, and a curtain pole bracket provided at its base with guide- 120 flanges taking over the upper and lower edges of said last mentioned bracket-head.

6. A shade and curtain fixture, comprising 125 an attaching and supporting-plate provided at its side with an angled extension terminat- ing in a hooked-flange and at its end with a bracket-head, a supporting-plate at the rear of said angled extension and provided at its

end with a bracket-head and at its lower edge with a hooked-flange and having its bent over edge impinging against said attaching and supporting-plate, and a curtain-pole bracket provided with a base having its upper and lower edges bent over forming guide-ways slidably-mounted on the upper and lower edges of said last mentioned bracket-head.

7. A shade and curtain fixture, comprising an attaching and supporting-plate provided at its rear with a guide-slot and at its front with a face-extension extending at right angles thereto and terminating in a hooked-flange, a supporting-plate carrying a bracket-head and provided with a hooked-flange taking into said hooked-flange and resting on said attaching and supporting-plate, and a curtain-pole bracket provided with a base

having guide-flanges taking over the upper and lower edges of said bracket-head.

8. In a shade and curtain fixture, the combination with a main attaching and supporting plate comprising a horizontal plate portion carrying at its front edge an upwardly-projecting face-extension terminating in a downwardly-extending hooked flange; of a supporting-plate carrying a bracket head and provided at its lower edge with a hooked-flange taking into and engaging with said downwardly-extending hooked flange.

In testimony whereof I have affixed my signature, in presence of two witnesses.

EDWARD E. PALMER.
